UNITED STATES PATENT OFFICE.

CHARLES E. WARNER, OF OTTAWA, KANSAS.

VEHICLE-JACK.

1,139,243.

Specification of Letters Patent.

Patented May 11, 1915.

Application filed May 14, 1914. Serial No. 838,565.

To all whom it may concern:

Be it known that I, CHARLES E. WARNER, a citizen of the United States, residing at Ottawa, in the county of Franklin and State 5 of Kansas, have invented a new and useful Vehicle-Jack, of which the following is a specification.

This invention relates to vehicle jacks and is more particularly designed as an improvement 10 upon the structure disclosed in an application filed by me on February 15, 1913, Serial No. 748,668.

One of the objects of the invention is to provide a jack which can be readily adjusted 15 for use in connection with vehicles of different lengths and which is provided with a novel arrangement of toothed elements whereby the structure is caused to operate positively.

With the foregoing and other objects in view which will appear as the description proceeds, the invention resides in the combination and arrangement of parts and in the details of construction hereinafter described and claimed, it being understood 25 that changes in the precise embodiment of the invention herein disclosed, can be made within the scope of what is claimed, without departing from the spirit of the invention.

In the accompanying drawings the preferred form of the invention has been shown.

In said drawings:—Figure 1 is a plan view of the jack. Fig. 2 is an enlarged side elevation of one pair of racks and the lifting gears engaging the same, the adjacent portions of the jack structure being shown. Fig. 3 is a view similar to Fig. 2 and showing 30 the parts shifted to the positions occupied thereby when the vehicle is supported out of contact with the ground. Fig. 4 is a section on line A—B Fig. 1. Fig. 5 is a side elevation of a modified form of lifting element, the position of the axle engaging finger when lowered, being indicated by dotted lines. Fig. 6 is a rear elevation of the structure shown in Fig. 5. Fig. 7 is a section through the gripping element. Fig. 50 8 is a front elevation thereof.

Referring to the figures by characters of reference 1 designates the side beams of a base frame, these side beams being connected, at each end, by cross beams 2 and 3 disposed

in pairs, the beams 2 being located at the 55 rear end of the frame and the beams 3 at the front end thereof. An intermediate cross beam 4 may connect the beams 1 adjacent their centers. Flanged plates 5 extend from the rear ends of the beams 1 and converge rearwardly as shown, these plates constituting deflectors so that, should a wheel come into contact with either of them, it would be deflected laterally, thus to insure straddling of the frame by the vehicle. As 60 shown, these plates 5 are slotted transversely, as at 6, to receive clamping bolts 7. Thus the deflecting plates can be adjusted toward or from each other.

Mounted on the beams 2 are parallel bars 70 8, each of which is formed with an integral rack bar 9 curved upwardly and forwardly, there being an upstanding guide flange 10 along the outer side of each rack bar and a reinforcing web 11 under each rack bar, as 75 shown particularly in Fig. 2. Ears 12 extend inwardly from the end portions of each bar 8 and bear downwardly on the beams 2, these ears being slotted longitudinally and adapted to receive clamping bolts 13. Thus 80 it will be seen that the bars 8 can be adjusted toward or from each other.

Supported by the front beams 3 are parallel bars 14 which extend downwardly between the beams 3 and are provided, between said beams, with straight rack bars 15 along the outer sides of which are provided guard flanges 16. Each of these guard flanges has a series of notches 17 in its upper edge. Ears 18 extend inwardly 90 from the end portions of each bar 14 and each of these ears is slotted longitudinally for the reception of a clamping bolt 19 engaging the beam 3 thereunder. Thus it will be seen that the rack bars 15 can be adjusted 95 toward or from each other upon the base frame.

Deflecting plates 20 are secured to the side beams 1 at points between the ends thereof, preferably opposite the rear ends of the bars 100 14, these plates 20 having upstanding flanges 21, the ends of which are extended inwardly, as shown in Fig. 1. These plates constitute means for deflecting the wheels of a vehicle outwardly from the base frame so that said vehicle will be properly centered over the frame while moving into position in engagement with the jack. As shown in Fig. 105

1, each of the plates 20 is slotted transversely for the reception of clamping bolts 22 whereby the plate can be secured adjustably to the base frame.

- 5 Longitudinal angle strips 23 are secured upon the middle portions of the beams 2, 3 and 4 and pivotally mounted between these strips adjacent the centers thereof is the lower end portion of an upwardly extending 10 gripping element 24 to the upper end of which is secured the rear end portion of a rod 25. The front end portion of this rod is secured to one arm of a bell crank lever 26 fulcrumed between the front end portions 15 of the strips 23, the other arm of said lever constituting a foot lever. A spring 27 is secured to the rear end of rod 25 and is connected, by a chain 28, to an upstanding bracket 29 secured between the strips 23.
- 20 A rod 30 is slidably mounted in the bracket 29 and extends loosely through the gripping member 24. The rear end of this rod is slidably mounted in a bracket 31 and a spring 32 bears at one end against the bracket 31 and at its other end against a nut or head 33 upon the rod, this spring thus operating normally to hold the rod 30 yieldingly in a predetermined position.

30 The strips 23 and the parts mounted thereon constitute an automatic locking structure which, specifically, forms no part of the present invention but has been fully disclosed in a copending application filed by me on December 18, 1918, Serial Number 35 807,530.

Mounted on each of the arcuate rack bars 9 is a segmental gear 34, the two gears being connected, off center, to a transverse shaft 35, each gear having an integral sleeve 40 36 extending inwardly therefrom through which the shaft extends, said sleeve being secured to the shaft by means of a set screw 37 or the like. An arm 38 extends from each gear 34 and radiates from the sleeve 36, this arm being provided upon its upper edge with an ear 39 in which a trunnion 40 is pivotally mounted, this trunnion extending inwardly from a sleeve 41. A cross strip 42 is secured to the rod 30 back of the 50 gripping member 24 and adjustably secured to this cross strip are the forward ends of forwardly converging strips 43 pivotally connected to the upper ends of the respective arms 38, as shown at 44, the rear 55 end of each of these strips 43 being formed with a yoke 45 disposed back of the adjacent segmental gear 34.

Supported by and engaging the rack bars 15 are segmental gears 46. Each of these 60 gears has an inwardly extending sleeve 47 disposed eccentrically thereon and extending through the sleeves and gears is a shaft 48, this shaft being fixedly connected to the gears by set screws 49 or in any other suit-

able manner. Each of the segmental gears 65 has an arm 50 formed with a U-shaped seat 51 in its end, the front wall of each seat being extended upwardly, and rounded as at 52 so as to constitute a finger for the purpose hereinafter set forth. A nose 53 is 70 extended forwardly and laterally from each gear and is adapted, when the gear is shifted to a predetermined position, to become seated in one of the notches 17, thus limiting the movement of the gear in one direction. Each gear 46 has a trunnion 54 mounted therein adjacent the base of its arm 50, said trunnion extending laterally from a sleeve 55. Mounted within the sleeves 41 and 55 are parallel connecting rods 56 and 80 set screws 57 are carried by the said sleeves and engage these rods for the purpose of holding the rods against movement relative to the sleeves. It is to be understood that the gears 34 and 46 are held by gravity 85 normally in the positions illustrated in Fig. 2, at which time the yokes 45 are supported below the path of the axles of a vehicle while the finger 52 extends upwardly into the path of the front axle of a vehicle. Consequently, when a vehicle is propelled longitudinally along the jack with its wheel traveling at opposite sides of the jack, the front axle of the vehicle will pass over the gear 34 and yokes 45 and, as the rear axle 90 assumes a position directly over the yokes 45, the front axle will strike against the upstanding fingers 52. The momentum imparted by the forwardly moving vehicle will cause the gears 46 to travel forward on the 100 racks 15 until the front axle, which assumes a position in the seats 51, is elevated above and slightly past the shaft 48 whereupon the noses 53 will become seated in certain of the notches 17 so as to limit the movement of the gears 46. During this actuation of the gears 46, the rods 56 will pull on the arms 38 and cause the gears 34 to travel forwardly and upwardly along the arcuate racks 9, thereby bringing the yokes 45 110 against the rear axle and elevating said axle so as to lift the rear wheels off the ground. As the gears are actuated in the manner described the rods 43 push the rod 30 forwardly so that it slides within the 115 gripping member 24 and as will be seen by referring to Figs. 7 and 8 said member will prevent the rod and, consequently the gears 34, from returning to their initial positions. By pressing against the foot lever 120 26, the clutch member 24 can be shifted out of gripping position so as to release the rod 30 and thus permit the gears 34 and 46 and the parts carried thereby to gravitate back to their initial positions whereupon the 125 wheels of the vehicle will be brought into contact with the ground.

Importance is attached to the fact that the

rack bars can be adjusted toward or from each other, thus permitting the structure to be adjusted to vehicles of different widths. Furthermore by loosening the set screws 57, 5 the gears 46 can be lifted out of engagement with the rack bars 15 and adjusted longitudinally of said bars, thus to adapt the jack to vehicles of different lengths.

Instead of providing the front gears 46 10 with integral upstanding fingers, as heretofore described, front gears 58 can be used, each of these gears having a forked portion 59 in which is pivotally mounted one end of an angular finger 60. This finger has one 15 end portion adapted to extend upwardly as at 61 when the finger is in its normal or active position, this upwardly extending portion 61 corresponding with the finger 52. When, however, it is desired to propel a 20 vehicle over the jack without actuating the lifting mechanism, this finger 60 can be shifted to the position indicated by dotted lines in Fig. 5, whereupon the front axle of the vehicle will not come into engagement 25 with the part 60 but will pass thereover without actuating the gears.

What is claimed is:—

1. In a vehicle jack, the combination with a base frame, of racks disposed in pairs and 30 mounted on the frame, the racks of each pair being adjustable toward and from each other, segmental gears supported by the respective racks, shafts adjustably mounted within and supported by the gears and constituting connections therebetween, connecting rods, adjustable connections between said rods and the gears, and means carried by the gears for engaging and elevating the axles of a vehicle when brought into position thereagainst.

2. A vehicle jack including a base frame, front and rear rack bars supported thereby and disposed in pairs, the bars of each pair being adjustable toward and from each 45 other, segmental gears mounted upon the respective rack bars, shafts connecting the gears and eccentrically mounted therein, connecting bars, adjustable connections between said bars and the corresponding front 50 and back gears, upstanding axle engaging fingers upon the front gear, there being seats adjacent the fingers for the reception of the front axle of a vehicle, means carried by the rear gears for engaging and supporting the rear axle of a vehicle.

3. A vehicle jack including a base frame, front and rear rack bars supported thereby and disposed in pairs, the bars of each pair being adjustable toward and from each 60 other, segmental gears mounted upon the respective rack bars, shafts connecting the gears and eccentrically mounted therein, connecting bars, adjustable connections between said bars and the corresponding front

and back gears, upstanding axle engaging 65 fingers upon the front gear, there being seats adjacent the fingers for the reception of the front axle of a vehicle, means carried by the rear gears for engaging and supporting the rear axle of a vehicle, the front 70 rack bars having notches therein, and means carried by the front gears for engaging the notched portions of the bars to limit the rotation of the gears in one direction.

4. A vehicle jack including a base frame, 75 front and rear rack bars supported thereby and disposed in pairs, the bars of each pair being adjustable toward and from each other, segmental gears mounted upon the respective rack bars, shafts connecting the 80 gears and eccentrically mounted therein, connecting bars, adjustable connections between said bars and the corresponding front and back gears, upstanding axle engaging fingers upon the front gear, there being 85 seats adjacent the fingers for the reception of the front axle of a vehicle, means carried by the rear gears for engaging and supporting the rear axle of a vehicle, and means for automatically holding the gears against 90 return movement when shifted out of their normal positions.

5. A vehicle jack including a base frame, front and rear rack bars supported thereby and disposed in pairs, the bars of each pair 95 being adjustable toward and from each other, segmental gears mounted upon the respective rack bars, shafts connecting the gears and eccentrically mounted therein, connecting bars, adjustable connections between said bars and the corresponding front and back gears, upstanding axle engaging fingers upon the front gear, there being 100 seats adjacent the fingers for the reception of the front axle of a vehicle, means carried by the rear gears for engaging and supporting the rear axle of a vehicle, the front rack bars having notches therein, means carried by the front gears for engaging the notched portions of the bars to limit the rotation of the gears in one direction, and means for automatically holding the gears against 110 return movement when shifted out of their normal positions.

6. A vehicle jack including a base frame, 115 deflecting plates adjustably connected to the sides and one end thereof, front and rear rack bars supported by the frame, said bars being disposed in pairs, the bars of each pair being adjustable laterally relative to 120 each other, a gear mounted on each bar, a shaft connecting the corresponding gears and constituting the sole connection therebetween, connecting bars, adjustable connections between said bars and the corresponding gears of the two pairs, locking mechanism, strips connecting the same to the rear gears for holding all of the gears against 125 re-

turn movement after being shifted out of normal positions, said strips having terminal yokes for engaging and supporting the rear axle of a vehicle, and means upon the front gears for engaging and supporting the front axle of a vehicle.

In testimony that I claim the foregoing

as my own, I have hereto affixed my signature in the presence of two witnesses.

CHARLES E. WARNER.
